Attorney

UNITED STATES PATENT OFFICE.

JOHN D. MILLER, OF NEWTON, NORTH CAROLINA.

COLLAPSIBLE TUBE CLOSURE.

Application filed March 19, 1926. Serial No. 95,941.

This invention relates broadly to an improved collapsible tube of the kind used for containing tooth paste, shaving cream, patching cement, paste, and the like, and it has 5 more specific reference to a novel closure for the discharge end of the tube and a new method of making the closure.

Briefly, the invention comprises a neck formed with a discharge passage and with a 10 spherical socket. A ball valve is fitted snugly, but freely movable in this socket, and this valve has a passage which is adapted to be aligned with the passage in said neck in order to permit the contents of the tube to 15 be dispensed. The valve is equipped with a right angular operating member accessible on the exterior of the neck and so arranged that it may be operated by the fingers of the hand in which the tube is held, whereby to 20 permit the valve to be closed and permit the other hand to be used for manipulating the tooth brush, or for otherwise using the tube contents.

One feature of construction is the neck 25 which is composed from lead and which is cast or molded about the valve, the valve being made of a more rigid material.

A second feature of construction is the operating handle for the valve which is in the 30 form of a finger actuated crank located on one side of the neck so that the valve can be easily opened and closed with the fingers of the same hand in which the tube is held.

A further feature of construction is the 35 making of the discharge neck in the form of a detachable unit capable of being applied to the ordinary screw threaded nipple of the conventional or marketed tube.

Other features and advantages will be 40 come apparent from the following description and drawings.

In the accompanying drawings forming a part of this application and in which like numerals are employed to designate like 45 parts throughout the same:

Figure 1 is an elevational view of the ball valve.

Figure 2 is a similar view of the valve showing a coating of material surrounding it such as is used in the new method of manufacture.

Figure 3 shows the structure represented in Figure 2 associated with the neck.

Figure 4 is a view showing the finished 55 valve and neck construction.

Figure 5 is a view showing the complete valve and neck construction together with a part of the tube.

Figure 6 is a detail sectional and elevational view showing the neck constructed as 60 an attachable unit to the customary threaded nipple of a conventional tube.

Referring to the drawings in detail, the reference character 1 designates the ball valve and 2 indicates the finger crank which 65 serves as an operating lever for the valve. The reference character 3 (see Figures 2 and 3) represent a coating of a certain kind of material around the valve. The reference character 4 designates the discharge neck 70 which is formed of lead. The top of the tube 5 is represented by the reference character 6.

As before stated, a new method is employed in making the structure shown. 75 First, the ball 1 is cast or molded into spherical form. This ball is made of glass or other suitable relatively hard metal. The right angular handle 2 is attached to the ball at the approximate point shown. The ball 80 and the part of the handle is then dipped into lard or oil and is sprinkled lightly with bicarbonate of soda to form the coating 3. The coated structure is then suspended by suitable means in a mold for 85 forming the neck 4. Melted lead is then poured into the mold around the coated sphere. The molten lead coming in contact with the bicarbonate of soda generates a gas which bubbles off and keeps the lead 90 from adhering closely to the ball.

The steps recited are somewhat illustrated in Figures 1, 2, and 3, wherein the ball is shown in its natural state, then coated with the bicarbonate of soda and oil, and then 95 as it appears before completely cooled. After the cast or molded neck cools, it is shaped as shown and a hole is bored through the ball and neck to form a passage 7 through the ball and a complementary passage 8 through the base portion of the neck. In the drawing, the neck is shown attached to the convex top portion 6 of the paste 100 containing tube. When the structure is thus completed, the ball is freely rotatable in the spherical socket thus provided and by turning the handle or crank 2 to the position indicated in Figure 4, the passage is completely open to permit discharge of the 105 contents from the tube, and by turning the 110

crank to the position shown in Figure 5, the passage is closed.

As before stated, instead of having the neck 4 integral with the top 6, the structure may be made as in Figure 6. Directing attention to this figure it will be seen that this neck 9 which is of similar shape, is formed with a spherical socket in which the ball valve 10 is fitted. The valve is provided with the usual central passage and with the operating crank 11. The neck however, has a conical socket or recess 12 formed in its bottom and a screw threaded passage 13 adapted to register with the passage in the ball valve. This form of the invention is adapted to serve as an attachment to fit on the usual screw threaded nipple of the ordinary marketed dispensing tube.

It is to be stated that in the method of making the structure hereinbefore set forth, it is permissible to bore the hole through the ball valve before it is coated and placed in the mold. At this time however the bore must be plugged with suitable material and the plug removed after the molding operation is completed.

From the foregoing description it will be seen that I have evolved and produced a novel valve serving as a closure for the discharge end of a dispensing tube for tooth paste and the like. The structure is not only novel, simple and inexpensive, but is of advantage due to the facility which may be exercised in the operation of opening and closing the tube. These features and others will no doubt be apparent to those skilled in the art to which the invention relates,

and in view of this a more lengthy description is thought unnecessary.

While the preferred embodiment of the invention has been shown and described, it is to be understood that minor changes coming within the field of invention claimed may be resorted to if desired.

Having thus described the invention, what I claim as new and desire to secure by Letters Patent is:—

As a new product of manufacture, an attachment for a conventional type of collapsible dispensing tube wherein said tube embodies a conical discharge end having a central externally screw-threaded discharge nipple, said attachment being in the form of a closure for said nipple and including a cylindrical body having a conical recess in its bottom to engage the conical end portion of said tube, a central screw-threaded bore into which said nipple is adapted to tap, a spherical socket in communication with said bore, and a discharge opening of a diameter less than said bore, and a ball valve fitted snugly in said socket but freely movable therein and having a portion to project through and beyond said discharge opening when the valve is in closing position, said valve having a passage adapted to register with said bore and discharge opening, and an operating crank for the valve extending at right angles to the longitudinal axis of the passage in said valve and mounted for movement upon said body.

In testimony whereof I affix my signature.

JOHN D. MILLER.
